UNITED STATES PATENT OFFICE.

LOUIS SIMPSON, OF OTTAWA, ONTARIO, CANADA.

RETORT.

Application filed March 10, 1920. Serial No. 364,849.

To all whom it may concern:

Be it known that I, LOUIS SIMPSON, a subject of the King of Great Britain, and resident of the city of Ottawa, Province of 5 Ontario, Dominion of Canada, have invented certain new and useful Improvements in Retorts, of which the following is a specification.

This invention relates to improvements in 10 retorts, particularly of a type designed to carry out the treatment of carbonaceous materials, such as oil shale for the purpose of recovering the hydrocarbon gases, vapours and oils contained therein, and the general 15 objects of the invention are to provide a simple and effective form of retort in which the treatment of the materials may be effected in the most economical and efficient manner possible, and in which the various parts 20 of the apparatus will most effectively perform the functions required of them.

More specific objects of the invention are to provide for the distribution of the inducted treating gases at different points 25 throughout the mass, and at the same time to provide for the eduction of the evolved gases.

Further objects still are to provide improvements in mechanism for feeding and 30 passage of the shale, and preventing over-heating of the apparatus.

It consists essentially of the improved 35 construction hereinafter described in detail in the accompanying specification and drawings.

In the drawings:—

Figure 1 is a sectional elevation of a retort embodying the invention.

Figure 2 is a sectional elevation taken at 40 right angles to Figure 1.

In the drawings, like characters of reference indicate corresponding parts in all the figures.

Referring to the drawings, A represents a 45 casing of the retort, constructed of suitable material, such as steel plate, bolted, riveted or welded together in accordance with the practice well known in the art.

The casing is divided internally into a 50 plurality of chambers B, by means of vertically extending partitions C, the top of which chambers open into a pocket or hopper D into which the material such as oil shale, which is to be treated is fed by any 55 convenient means, being directed into the openings of the chambers B by suitable de-

flecting plates 10, and being fed through the opening by suitable feeding means such as the paddle wheel feeding members 11 mounted on the transversely extending shaft 60 12, which is driven from any convenient source of power.

The lower part of each of the chambers B are constructed to form discharge outlets E above which suitable delivering mechanism 65 such as pairs of rolls F and G operate, and suitable V-shaped deflectors H, being placed beneath the opening of the rolls to deflect the shale to the outer sides of the outlets.

To cool the spent shale and recover there- 70 of as much heat as may be found desirable before the shale is removed from the chamber B, water jackets I are provided around the lower portion of the chambers, which jackets also surround the outlets E, and 75 through which jackets, water or other cooling liquid is circulated by any convenient means.

The spent shale passing through the outlet E is fed laterally by suitable spiral conveyors J driven from a suitable source of power, which delivers the spent shale into a continuously moving conveyor K of any suitable type, that shown being a belt conveyor. 85

The distillation, carbonization or vaporization of the shale or other material to be treated is effected by the introduction of fixed heated gases into the chambers B, and means are provided for introducing these 90 gases at different points throughout the chamber, and in such a way as to be uniformly distributed through the mass.

I have shown at the sides of each of the chambers B a plurality of tapered discharge 95 elements L having overlapping walls which form ports 13, through which the gas is inducted, the gases being supplied to ports 14 within the elements L by any suitable or convenient means.

It will be seen that as the walls 15 of the elements L are tapered they will not interfere, but rather facilitate the discharge of the shale through the chambers.

The hydrocarbon and other gases and va- 105 pors, liquids and volatile liquids and oils evolved in the distilling operation, together with the thick gases induced are designed to be educed at different points throughout the mass through the educting elements M, 110 which are also tapered and formed with overlapping walls, the lowermost element

having an inlet port 16, while the uppermost element has an inlet port 17.

A separate conductor 18 is designed to conduct the gases from the port 17, while the gases passing into the port 16 are inducted through the outlet 19, which is connected with suitable conductors which will lead the gases and vapours away for treatment and condensation in suitable treating and condensing apparatus.

It will be seen that the educting elements M are spaced between the inducting elements L and have their walls tapered, whereby clear passage will be provided between the two elements for the shale or other material being treated.

In carrying out the process, oil shale or other suitable material to be treated is introduced into the conductor D and fed through the chambers B where it is subjected to the heat by the passage therethrough of a super-heated fixed gas. The gas which is used may for instance be the incondensable portion of the gases educed, and will in that case be one or more of the light hydrocarbon series.

The heat treatment of the shale will result in the eduction of valuable gases, vapours and oils, which may be condensed and separated in the manner well known in the art.

The spent shale passes out as already explained, and is received by the conveyor K and may be subjected to such further treatment as desired.

It will be seen that owing to the simple construction of the inducting and educting elements, the ports and openings within may be readily kept clean and any deposit adhering to the walls may be easily removed without removing the plates.

The entire retort chamber may be suitably protected by heat insulating material, and the whole may be enclosed in re-enforced concrete.

The temperature to which the shale is heated may be determined by the amount of heat given to the fixed gases with which it is treated, and by the quantity of fixed gases supplied.

As many changes could be made in the above construction, and many apparently widely different embodiments of my invention, within the scope of the claims, constructed without departing from the spirit

or scope thereof, it is intended that all matter contained in the accompanying specification and drawings shall be interpreted as illustrative and not in a limiting sense.

What I claim as my invention is:

1. A retort for the treatment of carboniferous material comprising a plurality of vertically arranged chambers provided with deflector plates at the top opening into a single supply hopper for said chambers, means for feeding materials from the hopper to the chambers, discharge outlets in the lower part of the chambers, V-shaped deflectors therefor, and means for educting the spent materials through said outlets, a plurality of gas supply elements for the sides of the chambers formed with tapered overlapping walls adapted to provide gas induction ports therefor, ports within said elements and means for supplying heated gas thereto, a plurality of educting elements in spaced relationship to said supply elements in said chambers and similarly formed with tapered overlapping walls, inlets formed in the ends thereof, a body enclosing the elements, an outlet in the body and a conduit extending between the uppermost inlet and said outlet, jacket cooling means for said chambers, and heat insulating means for the retort.

2. A retort of the class described comprising a plurality of separate chambers provided with a single feed hopper common to all of said chambers, means for feeding materials from the hopper to the chambers, a discharge outlet for each chamber, and means for discharging the spent material therethrough, a plurality of gas inducting elements in the sides of each chamber, and means for supplying gas thereto, and an educting element in each chamber comprising a hollow body portion provided with an outlet and having the lower end thereof open to form an inlet, said body being further provided with a pocket open to the retort above said inlet, and a conduit extending between said pocket and said outlet, means for cooling the lower portion of the chambers, and heat insulating means for the retort.

In witness whereof I have hereunto set my hand in the presence of a witness.

LOUIS SIMPSON.

Witness:

RUSSEL B. SMART.
